UNITED STATES PATENT OFFICE.

EDWIN R. CLARK AND LEO R. NEUER, OF JOLIET, ILLINOIS.

DESIGN FOR A DOLL'S COSTUME.

59,193.

Specification for Design.

Patented Oct. 4, 1921.

Application filed April 11, 1921. Serial No. 460,496. Term of patent 7 years.

To all whom it may concern:

Be it known that we, EDWIN R. CLARK and LEO R. NEUER, both citizens of the United States, residing at Joliet, in the county of Will and State of Illinois, have invented a new, original, and ornamental Design for a Doll's Costume, of which the following is a specification, reference being had to the accompanying drawing, forming part thereof.

We claim:

The ornamental design for a doll's costume as shown.

EDWIN R. CLARK.
LEO R. NEUER.
